(57) **CLAIM**

The ornamental design for a vacuum gripper as shown and described.

DESCRIPTION

FIG. 1 is a top perspective view of a vacuum gripper, showing my new design;

FIG. 2 is a top elevational view thereof.

FIG. 3 is a bottom elevational view thereof.

FIG. 4 is a right elevational view thereof.

FIG. 5 is a left elevational view thereof.

FIG. 6 is a front elevational view thereof.

FIG. 7 is a rear elevational view thereof; and,

FIG. 8 is a bottom perspective view thereof.

The broken lines in the drawings depict portions of the vacuum gripper that form no part of the claimed design.
